UNITED STATES PATENT OFFICE.

JOHN H. KRUEPANY, OF ROSSFORD, OHIO.

PLATE-GLASS WASHING AND CLEANING APPARATUS.

Application filed April 17, 1922. Serial No. 553,488.

To all whom it may concern:

Be it known that I, JOHN H. KRUEPANY, a citizen of the United States, and a resident of Rossford, in the county of Wood and State of Ohio, have made an Invention Appertaining to a Plate-Glass Washing and Cleaning Apparatus; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to the manufacture of plate glass and particularly to an apparatus for cleaning the glass after a polishing or grinding operation.

In the grinding or polishing of plate glass it is customary to secure the glass to a table by the application of a cementitious material to the under surface of the sheets, or the surface thereof next to the table, and when the glass is removed from the table a large part of this material adheres thereto. To remove such material an acid is usually applied to loosen the same and the glass surface is then washed free of the material.

The object of the invention is the provision of a simple apparatus for handling the glass sheets during the cleaning operation and adapted to wash and dry the same in a rapid and efficient manner.

The invention is fully described in the following specification, and while, in its broader aspect, it is capable of embodiment in numerous forms, a preferred embodiment thereof is illustrated in the accompanying drawings, in which,—

Fig. 1 is a front elevation of an apparatus embodying the invention with the opposite end portions thereof broken away. Figs. 2 and 3 are vertical cross sections thereof on the lines 2—2 and 3—3, respectively, in Fig. 4. Fig. 4 is a fragmentary rear elevation of a part of the apparatus, and Fig. 5 is a fragmentary sectional plan view of a portion thereof together with the driving means for the operating parts.

Referring to the drawings, 1 designates a skeleton form of frame, which is disposed in slightly inclined upright position and

comprises a longitudinally extending base or sill member 2, a plurality of spaced upright members, and a plurality of spaced horizontal members 4 connecting the uprights 3. In the present instance two of the frames 1 are employed in longitudinally aligned relation and slightly spaced apart at their adjacent ends, the frames being mounted in any suitable manner in slightly inclined upright position. The sill strips 2 of the frames are provided at their front sides with a plurality of spaced glass plate supporting rolls 5, which are fixed to the shafts 6 that project through the respective sill strips and are mounted at their rear ends in supporting bearings 7. The rolls are fixed to the shafts for rotation therewith and each shaft or any desired number of the shafts has a sprocket-wheel 8 thereon at the rear of the frame and in engagement with a sprocket-chain 9, which extends the entire length of the apparatus in driving engagement with all of the sprocket wheels 8 thereof. One of the shafts 6 has a rearward extension 10 in driven connection, through a set of gears 11, with a drive shaft 12 disposed at the rear of the apparatus and journaled in bearings 13, and this shaft, in the present instance, is in belt and pulley connection 14 with a motor 15, or other suitable driving source.

Successive plates of glass 16 are intended to rest at their lower edges on the rolls 5 and to be moved by rotation of such rolls from one end to the other of the apparatus, the plates taking substantially the incline of the frames and resting freely at their rear sides against guide members 17 projecting from the horizontal frame strips 4 at a predetermined point in a movement of the plates along the frames 1.

A post or upright 18 rises from the foundation 19 in advance of the frames 1, and in the present instance, adjacent to their inner ends and carries a plurality of brackets 20 in which shafts 21 are journaled. Each shaft 21 carries a rotary brush 21 at its inner end in position for the brush to have scrubbing engagement with the front surface of a sheet 16 as it passes along the frames 1. The brushes 22 in the present instance, are three in number and arranged in vertically spaced staggered relation. The

several shafts 21 have chain and sprocket wheel connections 23 to cause them to rotate in unison, and one of the shafts has chain and sprocket wheel connection 24 with the 5 forwardly extended end of one of the shafts 6. It is thus evident that the brushes are driven by the same driving means as the rolls 5.

Water or other cleaning liquid is discharged 10 against the front surface of the glass plate 16 above the brushes 22 from a nozzle 25, which is in communication with a suitable source of supply through a pipe 26. The foundation 19 is provided with a 15 drainage passage 27 below the brushes or point of application of water to the glass plates.

The glass plates 16, after passing beyond the scrubbing members 22 are engaged at 20 the front sides thereof and also preferably at the rear sides by sets of wiper strips 28 carried by screws 29 for adjustment inward and outward with respect to the plates. The screws of the front set of wiper strips 25 thread through a front standard 30, and those for the rear set of wipers extend through an upright member 31 of the frame. The wipers 28 of each set preferably lap each other at their ends so that the 30 entire surface of a glass plate as it passes along the frame is wiped by the wiper strips.

It is intended to apply an acid to the cemented surfaces of the glass plates before 35 the plates reach the scrubbing members 22, and it is preferable to have a pool or basin 32 provided in the foundation 19 below the point of application of the acid to the sheets to catch the acid flowing down 40 from the sheets, thereby enabling such acid to be used over and over. The acid may be applied to the sheets by a brush or in any other suitable manner, as well understood in the art.

45 In the use of my apparatus, glass sheets to be cleaned are successively placed on the rolls 5 at the left end of the apparatus and fed slowly forward to the right end of the apparatus by the rotation of the rolls. 50 When a sheet is over the acid bath 32 the acid is applied to the front surface thereof to soften the cement adhering thereto, and a considerable portion of the cement will fall from the sheet by reason of the acid 55 action. The remaining portion of the cement is brushed from the sheets by the scrubbing action of the brushes 22 and the flowing of the water or other cleaning liquid thereon, after which the sheets pass between 60 the wiping strips 28 which remove any water, cement or other matter remaining thereon. The rear set of wipers is intended merely to wipe the rear sides of the sheets of water or other liquid which may have been 65 accidentally applied thereto.

It is evident that I have provided an apparatus which is operable to automatically feed glass sheets in successive order from one end to the other of the guiding frames past the acid applying point and in successive contact with the brushing and wiping means, so that when a sheet is delivered from the forward end of the apparatus it is clean and dry. The use of this apparatus, so far as I am aware, effects a material saving both in labor and expense over the methods now employed for cleaning plate glass after being removed from the grinding tables.

I wish it understood that my invention is 70 not limited to any specific construction, arrangement or form of the parts, as it is capable of embodiment in numerous forms without departing from the spirit of the 75 claims.

Having thus described my invention, what I claim as new, and desire to secure by Letters Patent, is,—

1. In an apparatus of the class described, means for guiding the successive movements of glass sheets disposed at an angle to a horizontal, means for moving sheets in successive order lengthwise of the guiding means, and means operable to impart a scrubbing action to the sheets at a predetermined point in their movement.

2. In an apparatus of the class described, a horizontally elongated substantially upright sheet glass guiding means, rolls mounted at the lower portion of the means 100 for supporting sheet glass in upright position thereagainst and operable to impart movement to the sheets lengthwise of the guiding means, means operable to rotate the rolls, and scrubbing means operable to 105 act on the sheets when at a predetermined point in their movements lengthwise of the first means.

3. In an apparatus of the class described, a horizontally elongated substantially upright sheet glass guiding means, rolls mounted at the lower portion of the means for supporting sheet glass in upright position thereagainst and operable to impart movement to the sheets lengthwise of the 115 guiding means, means operable to rotate the rolls, scrubbing means operable to act on the sheets when at a predetermined point in their movements lengthwise of the first means.

4. In an apparatus of the class described, an inclined guide means, means for supporting a sheet of glass in inclined position against the guide means and imparting movement to the sheet lengthwise of the 125 means, rotary brush means for acting against a surface of a sheet at a predetermined point in its movement, and means for applying a liquid to the surface of the sheet 130 acted on by the brush means.

5. In an apparatus of the class described, a guide means, means for supporting a sheet of glass at an angle to a horizontal against the guide means and imparting movement to the sheet lengthwise of the guide means, means for applying a liquid to a surface of a sheet at a predetermined point in its movement relative to the guide means, and means in advance of the liquid applying means for wiping the sheet. ¹⁰
In testimony whereof I have hereunto subscribed my name to this specification.

JOHN H. KRUPEANY.
